SHAMPOO LAVATORY

James N. Mayhew, Los Angeles, Calif.

Application March 6, 1939, Serial No. 259,987

7 Claims. (Cl. 4—159)

This invention relates generally to the art of cosmetology, and more particularly to plumbing fixtures as used in beauty shops for hair washing and shampooing operations.

5 An object of this invention is to provide a lavatory structurally characterized by extremely simple and highly effective means forming a neck rest so associated with and related to the bowl portion of the lavatory that the operator will have ample working space for the hands and for the usual water spray device, in the bowl underneath and around the neck of the patron at the lavatory, so as to enable such relatively inaccessible part of the hair to be thoroughly shampooed with 10 ease and dispatch, and to be as thoroughly rinsed by convenient manipulation of the spray device close to the skin in order to avoid the discharge of uncontrolled jets of water from the device out of the bowl.

20 Another object of this invention is to provide a lavatory of the above described character in which the novel neck rest structure is related to the top of the bowl in a manner to enable the operator to perform the shampooing and rinsing operations with the hands extended into the bowl underneath the head of the patron, from one side of the bowl or the other and in a natural position wherein the operator stands at the side of the lavatory, rather than an unnatural one resulting from the operator being required to stand in front of the lavatory and to lean directly over the face of the patron, as is practically unavoidable with shampoo lavatories heretofore available.

25 A further object of the invention is to provide a shampoo lavatory in which the novel neck rest structure is removably associated with the lavatory in an extremely simple manner, and is constructed so as to be readily sterilizable without injury thereto, all while affording the aforesigned advantages of working space for the operator below and around the back of the neck of the patron, and in addition, of forming an extremely comfortable cushioned or soft yielding support 30 for the neck.

40 With these and other objects in view, the invention resides in the combinations, arrangements and functional relationships of elements as set forth in the following specification and particularly pointed out in the appended claims.

45 In the accompanying drawings:

Figure 1 is a plan view of a lavatory illustrating one form of the invention;

50 Figure 2 is a view in front elevation, of the lavatory shown in Figure 1;

Figure 3 is a vertical sectional view taken on the line 3—3 of Figure 2;

Figure 4 is a fragmentary sectional view taken on the line 4—4 of Figure 2;

Figure 5 is a view in front elevation of the 5 lavatory embodying another form of this invention;

Figure 6 is an enlarged fragmentary sectional view taken on the line 6—6 of Figure 5.

Referring specifically to the drawings, and 10 particularly to Figures 1 to 4, inclusive, the lavatory 10 embodying this invention includes a relatively deep bowl 11 having the usual drain opening 12 for connection to a drain pipe by suitable piping (not shown). From the rear wall 13 15 of the bowl projects a shelf 14 having hot and cold water valves 15 and 16 secured thereon and adapted for connection to suitable sources of water supply (not shown). A goose-necked spray pipe 17 is connected to the outlets of the 20 valves 15 and 16 and has attached thereto a suitable flexible hose 18 provided with a spray head 19.

The side walls 20 of the bowl 11 terminate at 25 a level considerably lower than that of the shelf 14, and merge into outwardly and downwardly rolled rims 21. The upper edges of the side walls 20 join the upper edges of the front wall 22 in relatively large outwardly and upwardly curved portions 23 as viewed in plan and front elevation, 30 respectively; and these portions are joined by an inwardly and downwardly curved portion 24 as viewed, respectively, in plan and front elevation, all with respect to the bowl 11, and so as to provide at the front of the bowl a saddle shaped 35 structure constituting a neck rest 25.

The outwardly and downwardly rolled rims 21 40 continue along the portions 23 and decrease in width to merge into the outer surface of the front wall 22 approximately at the joinder of the 45 curved portion 24 with the portions 23 as indicated at 26 in Figure 1.

The upper edge of the portion 24 is rounded and extended inwardly at a convenient upward angle over the bowl 11 to form an inwardly projecting lip 27 to provide the neck rest 25 with sufficient width to form a comfortable support for the back portion of the neck of a person when leaning backward from a seated posture in front of the lavatory. The lip 27 defining the neck 50 rest 25 co-acts with the front wall 22 of the bowl in providing beneath the lip from its free edge to the inner surface of the front wall a working space 28 which is essential to the convenient and thorough performance of various operations, as 55

will be later described in the operation of the invention. It will be noted that the lowermost and central point *a* of the neck rest 25 is at a considerably higher level than the top surface *b* of the side walls 20 as most clearly appearing in Figure 3, and for a purpose to be described in the operation and use of the lavatory, which is as follows:

With a patron seated at the lavatory, and her neck supported on the neck rest 25, the working space 28 provides ample room for the hands of the operator in shampooing the otherwise comparatively inaccessible portions of the hair at the base of the head and back of the neck, all without disturbing the patron or requiring that the head be temporarily lifted to an uncomfortable position clear of the neck rest to render such parts of the hair accessible for washing and rinsing. The working space 28 permits convenient manipulation of the spray head 19 close to the skin during the rinsing of the hair so as to obviate the discharge of uncontrolled water jets from the spray head and out of the bowl, when the spray head is held at a distance below the head of the patron, as is unavoidable in shampoo lavatories heretofore proposed, due to the lack of working space at the most essential location in the bowls thereof.

Furthermore, it will be noted that due to the higher level of the neck rest 25 to the top of the rims 21 at the side walls 29, as is clearly illustrated by the relationship of the points *a* and *b* in Figure 3, the hands of the operator can be very conveniently extended over the sides 29 of the bowl and underneath the head of the patron for the shampooing and rinsing operation, all while the operator is standing at one side or the other of the lavatory in a natural position enabling the hands to be more effectively used in such operations than is possible with shampoo lavatories of the prior art which by their construction require the operator to stand in front of a lavatory over the face of the patron in order to reach the back of the patron's head with the hands of the operator in comparatively unnatural positions which preclude, if not prevent, thoroughness in the work.

Referring now to Figures 5 and 6, the lavatory 13a herein shown is similar in construction to the lavatory 10 with the exception that the neck rest 25a of the former is constructed as a separate unit capable of being readily applied to the lavatory and as easily removed therefrom for thorough sterilizing without injury.

The neck rest 25a is constructed to provide a sheet metal foundation or base member 30 of a plan and elevational contour conforming to that of the central inwardly and downwardly curved portion 24a of the front wall 22a. The member is substantially U-shaped in cross section to provide inner and outer flanges 31 and 32, respectively, spaced to slidably receive the front wall 22a which is provided with a slot 33 from its upper edge, adapted to receive a stud 34 fixed to the inner flange 31 and having a suitable wing nut 35 for securely clamping the neck rest in place. The member is covered with a body 36 of suitable soft or yieldable material such as rubber which can be vulcanized to the member so as to become a permanent part thereof and is readily sterilizable.

The body 36 is formed to provide the lip 27a

which projects into the bowl of the lavatory and functions to provide the aforescribed working space with all its advantages, and in addition, to afford an extremely comfortable cushioned support for the patron.

What is claimed is:

1. A shampoo lavatory having means defining a neck rest in one vertical wall of the bowl thereof, and including a lip projecting from said wall into the bowl sufficiently to provide a working space in the bowl underneath the lip between its free edge and the inner surface of said wall, for the purpose described.

2. A shampoo lavatory having a neck receiving portion in a vertical wall of the bowl thereof; and means co-actable with said portion to provide a neck rest projecting into the bowl from said wall thereof, to define beneath the neck rest, a sufficient working space in the bowl for manipulation of the hands of an operator, and of a spraying device in shampooing and rinsing operations.

3. A shampoo lavatory having a neck receiving portion in the front wall of the bowl thereof; and means co-actable with said portion to provide a neck rest projecting into the bowl from said front wall thereof, and defining, beneath the neck rest, a sufficient working space in the bowl for manipulation of the hands of an operator, and of a spraying device in shampooing and rinsing operations; the side walls of the lavatory terminating at a level sufficiently lower than the neck rest for the arms of the operator to be extended from the sides of the bowl into the latter for convenient manipulation of the hands within said working space, while the operator occupies a position at one side or the other of the lavatory.

4. A shampoo lavatory having a neck receiving recess in a vertical wall of the bowl thereof; and an integral lip projecting inwardly of the bowl from the edge of the recess for co-action therewith in providing a neck rest in the bowl and a working space therein beneath the lip.

5. A shampoo lavatory having a neck receiving recess in a vertical wall of the bowl thereof; a neck rest including a laterally projecting neck supporting portion including a neck; and means co-acting with said wall and portion to detachably secure the neck rest to the wall with said lip projecting into the bowl to provide therein sufficient working space between said vertical wall and the underneath portions of a person's head supported by the neck rest for convenient manipulation of the hands of an operator.

6. A shampoo lavatory having a neck receiving recess in a vertical wall of the bowl thereof; a sterilizable neck rest having a rigid base member and a cover of yieldable material including a laterally projecting neck supporting portion; and means for detachably securing the neck rest to the lavatory with said portion disposed in the bowl.

7. A shampoo lavatory having a neck receiving recess in a vertical wall of the bowl thereof, and a slot extending from said recess; a sterilizable neck rest including a laterally projecting neck supporting portion and a pin adapted to be received in said slot to correlate the neck rest and lavatory with said portion projecting in the bowl; and means co-acting with said pin to detachably secure the neck rest in place.

JAMES N. MAYHEW. 70
